UNITED STATES PATENT OFFICE.

STEPHEN D. BAKER, OF NEW YORK, N. Y.

DESIGN FOR A COMBINATION SOAP AND TOOTHBRUSH HOLDER.

Application filed December 31, 1921. Serial No. 526,394. Term of patent 14 years.

To all whom it may concern:

Be it known that I, STEPHEN D. BAKER, a citizen of the United States, and a resident of New York city, in the county of New York and State of New York, have invented a new, original, and ornamental Design for a Combination Soap and Toothbrush Holder of which the following is a specification, reference being had to the accompanying drawings, forming part thereof.

In the drawings:

The figure is a perspective view of a bathroom fixture comprising a combination soap and tooth brush holder embodying my design.

I claim:

The ornamental design for a combination soap and toothbrush holder as shown.

STEPHEN D. BAKER.
